US00D722739S

(12) **United States Design Patent**
Kay et al.(10) **Patent No.:** US D722,739 S
(45) **Date of Patent:** ** Feb. 17, 2015(54) **FINANCIAL TRANSACTION TERMINAL**

(75) Inventors: **Christopher E. Kay**, Palo Alto, CA (US); **Ricardo Outi**, Singapore (SG); **Sopnendu Mohanty**, Singapore (SG); **Michael Ely**, Berkeley, CA (US); **Hector J. Moll-Carrillo**, San Francisco, CA (US); **Samuel Kong-Yue Lising**, San Francisco, CA (US); **Isao Takezawa**, San Francisco, CA (US); **Timothy Mathew Kobe**, Singapore (SG)

(73) Assignee: **Citibank, N.A.**, New York, NY (US)

(**) Term: **14 Years**

(21) Appl. No.: **29/394,302**

(22) Filed: **Jun. 15, 2011**

(51) LOC (10) Cl. **20-01**

(52) U.S. Cl.

USPC **D99/28**

(58) **Field of Classification Search**

USPC ..... (57) **CLAIM**

The ornamental design for a financial transaction terminal, as shown and described.

DESCRIPTION

A portion of the disclosure of this patent document contains material which is subject to copyright protection. The copyright owner has no objection to the facsimile reproduction by any one of the patent document or the patent disclosure, as it appears in the Patent and Trademark Office patent file or records, but otherwise reserves all copyright rights whatsoever.

FIG. 1 is a perspective view of a financial transaction terminal showing our new design;

FIG. 2 is another perspective view thereof;

FIG. 3 is a front view thereof;

FIG. 4 is an enlarged portion of the perspective view taken along lines 4-4 in FIG. 1;

FIG. 5 is an enlarged portion of the front view taken along lines 5-5 in FIG. 3; and,

FIG. 6 is an enlarged portion of the front view taken along lines 6-6 in FIG. 3.

The broken lines shown in the drawings represent portions of the financial transaction terminal that form no part of the claimed design.

1 Claim, 5 Drawing Sheets
